UNITED STATES PATENT OFFICE.

FREDERICK HARPER, OF CHICAGO, ILLINOIS.

MOLD FOR MAKING GARBAGE-RECEPTACLES AND THE LIKE.

1,295,489.

Specification of Letters Patent. Patented Feb. 25, 1919.

Application filed June 19, 1917. Serial No. 175,589.

To all whom it may concern:

Be it known that I, FREDERICK HARPER, a citizen of the United States, and a resident of the city of Chicago, county of Cook, and 5 State of Illinois, have invented certain new and useful Improvements in Molds for Making Garbage-Receptacles and the like, of which the following is a specification.

My invention relates to improvements in 10 molds for making garbage receptacles and the like, and has for its object the provision of a simple and efficient construction of this character which is readily collapsible and by means of which articles, such as garbage 15 receptacles, may be formed with great economy and expedition.

The invention consists in the combinations and arrangements of parts hereinafter described and claimed.

20 The invention will be best understood by reference to the accompanying drawings forming a part of this specification, and in which,

Figure 1 is a longitudinal vertical section 25 of a form embodying my invention,

Fig. 2, a top plan view of the same,

Fig. 3, a front end view of the same,

Fig. 4, a vertical transverse section of the same,

30 Fig. 5, a perspective view of a garbage receptacle formed in the form illustrated in Figs. 1 to 4 inclusive,

Fig. 6, a vertical longitudinal section of said receptacle,

35 Fig. 7, a horizontal section taken on line 7-7 of Fig. 6, and

Fig. 8, a vertical section taken on line 8-8 of Fig. 6.

The preferred form of construction as 40 illustrated in the drawings, comprises a suitable base member 9 having a raised central portion 10 as indicated. An outer form member is arranged upon said base member and consists of side members 11 and front 45 and rear members 12 and 13 respectively positioned on said base member against the sides of the elevated portion 10, the end members being grooved to receive the ends of the side members and the side members 50 being provided with vertical angle irons 14 adapted to be clamped to the ends of the front and rear members by means of wood clamps 15 as indicated. The side members 11 are provided with upward extensions 11' 55 at their rear portions and a cross strip 16 grooved to receive the forward end of the

extensions 11', the extensions 11' being provided with angle irons 14' by means of which the strip 16 may be clamped in place.

A hollow core member 17 is arranged to 60 be suspended within the outer form member above described, said core member being open at the bottom as indicated to permit of finishing of the upper surfaces of the bottom of the receptacle formed in the form. 65 The core member 17 projects at its forward end through a suitable opening provided in the front wall 12 and is secured in place at the top and sides by means of angle irons 18 as indicated. A strip 19 is arranged 70 across the inner upper portion of the front wall 12 and carries an angle iron 20 at its upper rear portion, said strip serving to form a space for the reception of the door of the garbage receptacle formed in the 75 form and the angle iron 20 serving to form a recess for the reception of a portion of said door. Angle irons 20' are arranged along the sides of core member 17 to provide door receiving grooves in the sides 80 of the receptacle formed and a strip 21 is arranged across the bottom of the opening in the front wall 12 to form a beveled ledge at the bottom of the door space as shown. The core member 17 is supported 85 at the rear by means of a strip 22 secured to the rear wall 13 and co-extensive with and secured to the rear of said core member as indicated, the core member being provided with an upward rear extension 17' for the 90 purpose. Angle irons 23 are arranged about the sides and forward portion of the extensions 17' to provide door receiving grooves and the strip 22 forming a door receiving 95 space, as indicated. By this arrangement it will be observed that when the hollow spaces between the outer form member and the inner core member are filled with concrete or other plastic material, a garbage receptacle 24 will be produced having door 100 spaces 25 and 26 grooved for the reception of doors 27 and 28, as indicated.

In use the mold is assembled as indicated in the drawings, and the hollow spaces between the walls thereof filled with a 105 cement or concrete mixture in a semi-liquid or plastic state, sufficiently liquid or plastic to flow under the strips 20 and 22 and to be shaped thereby. When the material thus inserted is sufficiently set the form or mold 110 is removed therefrom. The outer portion of the mold is preferably removed first,

which may be readily done by loosening the clamps 15 as will be understood. Thereupon the inner form member or core is removed. This is preferably accomplished by 5 first loosening the top of the forward portion of the core member which upon being slightly tilted may be readily removed through the open end thereof. Then the main side portions of the core member are 10 removed by releasing the same from the rear wall and upward extension 17' and drawing the same forwardly. Then the rear wall and upward extension may be readily removed by drawing the same out 15 vertically, and should there be any sticking, these parts may be readily taken apart to facilitate such removal. The receptacle is then lifted from the base member of the mold, when it is completed and ready for 20 use.

While I have illustrated and described the preferred form of construction for carrying my invention into effect, this is capable of variation and modification without departing from the spirit of the invention. 25 I, therefore, do not wish to be limited to the precise details of construction set forth, but desire to avail myself of such variations and modifications as come within the scope 30 of the appended claims.

Having described my invention what I claim as new and desire to secure by Letters Patent is:

1. A construction of the class described 35 comprising an outer form member open at the top; and an inner core member suspended within said outer form member and projecting through the forward wall thereof; and angle irons arranged on the sides 40 of said core member and adjacent the forward end thereof and positioned to form door guiding grooves in the inner walls of the molded article, substantially as described.

2. A construction of the class described

Copies of this patent may be obtained for five cents each, by addressing the "Commissioner of Patents, Washington, D. C."

comprising an outer form member open at 45 the top; an inner core member suspended within said outer form member and projecting through the forward wall thereof; and a suspending strip co-extensive with the rear upper edge of said core member and spanning the space between the rear side of said core member and the rear wall of said outer mold member, substantially as described. 50

3. A construction of the class described comprising an outer form member open at 55 the top; an inner core member suspended within said outer form member and projecting through the forward wall thereof; angle irons arranged on the sides of said core member and adjacent the forward end 60 thereof and positioned to form door guiding grooves in the inner walls of the molded article; a strip arranged across the top of said core member adjacent the forward edge thereof; and a separating strip co-extensive 65 with the rear upper edge of said core member and spanning the space between the rear side of said core member and the rear wall of said outer mold member, substantially as described. 70

4. A construction of the class described comprising an outer form member, made up of detachable side and end members, some of said members projecting beyond the others; clamp securing members on said other members, distanced slightly from said projections; clamps engaging said projections and said clamp securing members to hold said sides and ends in place; and a core member arranged within said outer form 80 member, substantially as described. 75

In testimony whereof I have signed my name to this specification in the presence of two subscribing witnesses.

FREDERICK HARPER.
